UNITED STATES PATENT OFFICE.

CHARLES GILBERT HAWLEY, OF CHICAGO, ILLINOIS, ASSIGNOR, BY MESNE ASSIGNMENTS, TO CENTRIFIX CORPORATION, OF CLEVELAND, OHIO, A CORPORATION OF DELAWARE.

CENTRIFUGAL FIXTURE.

Application filed November 28, 1924. Serial No. 752,718.

To all whom it may concern:

Be it known that I, CHARLES GILBERT HAWLEY, a citizen of the United States, residing at Chicago, Cook County, Illinois, have invented certain new and useful Improvements entitled Centrifugal Fixtures, of which the following is a specification.

In all processes of distillation and evaporation, and throughout the arts of fluid purification and rectification, as by separators, it is both assumed and desired that the fluid evolved or treated shall leave the drum or container in a pure state, free from foreign substances, such as heavier liquids and solids. But as a rule the conditions controlling and modifying the operation in some measure defeat this primary expectation and purpose, and, eventuate in producing or permitting the escape of impure fluids.

The present invention comprises a centrifugal fixture; that is, a device which does not itself move or rotate, but nevertheless reliably induces a strong centrifugal action within the escaping or discharged fluid and whereby the foreign substances are certainly and definitely removed from the flowing or escaping fluid, and either returned to the container or discharged externally if it be desired to rid the container thereof.

The objects of the invention are to perfect such processes of purification and to provide the simplest and most reliable device or apparatus for the performance of the perfected process. These objects and the specific character of the invention will presently appear in further detail.

The invention will be readily understood on reference to the drawings which form part of this specification, in which:

Fig. 1 is a longitudinal vertical section of a steam boiler, drum or the like equipped with a centrifugal fixture embodying this invention. Fig. 2 is an enlarged cross section thereof substantially on the line 2—2 of Fig. 1. Fig. 3 is a top view of the centrifugal fixture, partly in section on the line 3—3 of Fig. 2. Fig. 4 is a horizontal section on the line 4—4 of Fig. 2. Fig. 5 is like unto Fig. 4, differing only as to the shape of the tuyère blades. Fig. 6 is a vertical section of the device modified by the inclusion of the depending guard or hood, and Fig. 7 is a like view illustrating an upstanding guard or hood; and also shows

how the two main members of the device are fastened together.

Referring to Figs. 1 and 2, 1 represents the pressure drum, 2 the liquid level therein, 3 the outlet opening and 4 the nozzle proper. It will be seen that the offtake pipe 4' joins the nozzle. The end of the drum contains the usual manhole 1', with its cover-plate 1''. But for the presence of the novel apparatus comprising this invention, the fluid or vapor leaving the steam space or other chamber 5 would pass directly to the nozzle 4. Instead, this novel apparatus, though composed of parts all of which are stationary, that is non-rotative, subjects the escaping fluid to a rapid whirling action. In consequence of this rapid whirling action all substances heavier than the fluid are quite effectively separated therefrom, and, just before the fluid leaves the outlet, are completely separated therefrom.

In its best form the apparatus comprises two main portions, to wit, the top member 6 and the bottom member 7. The upper part of the member 7 fits into the bottom of the member 6 and most conveniently the parts are fixedly, though separably, attached one to the other as by means of a plurality of bolts 8 and pressure clips 9, see Figs. 3 and 7. It may be at once explained that as the parts must needs be introduced through the manhole 1' they must be of a size to permit such introduction. The device as a whole primarily takes its size from that of the outlet 3 to be served. Manholes are of standard size. The smaller sizes of this apparatus may be introduced intact, but the larger sizes must be made in separate parts, and devices of the largest sizes, though rarely requiring top members 6 which are made in two parts, usually are fitted with lower parts, i. e., tuyère rings 7 which, for convenience of introduction, are made in two parts.

The top member 6 is of generally circular form and is hollow. It is preferably a metal casting, so that all its portions may be integral; thus it is provided with the ears 8' for the bolts 8; with the upstanding portion 6^a; with the tangential nozzle portion 6^b, and with the oppositely extending supporting arms or brackets 6^c. The latter contain slotted openings 6^d and receive the bolts 10 by which the member 6 is bolted to or against the top of the drum 1.

It will now be apparent that the member 6 is essentially a hollow ring. The upstanding part 6^a is a collar, which is larger than the outlet 3 of the drum. Its top is shaped 5 to fit against the top of the drum and make a tight joint therewith. In lieu of a joint at this point the joint may be established between the top of the member 6 and the nozzle 4, as by means of a short nipple or 10 sleeve, such as is shown by the dotted lines 1—1 of Fig. 2. The nipple seats against the top of the member 6 and obviously is pushed up into the nozzle 4 by the pressure of the supporting bolts 10. When the nipple shown 15 by dotted line is used collar 6^a is not used. In the top of the hollow ring proper is the central opening 6^e. In its bottom is the larger central opening 6^f. Between the two is the still larger annular cavity or centrifugal race 6^g, the bottom 6^h of which is beveled or coned to merge with the margin of the large opening 6^f. The portion 6ⁱ, forming the top of the cavity 6^g, surrounding the outlet opening 6^e, markedly overhangs the 20 larger opening 6^f. A slight inclination downward toward the center may or may not be given the annular top surface 6ⁱ. Within the portion 6^b is the tangential discharge nozzle 6^j, the walls of which intersect 25 the periphery of the race 6^g and tangentially merge therewith. A pipe nipple 6^k in the part 6^b completes the top member 6. It remains, however, to be noted that the annular bottom surface 6^l of the member 6 contains 30 a seat or centering sink, which conveniently receives the top of the lower member or tuyère 7.

A discharge pipe 12, jointed at 12' to the nipple 6^k of the member 6, leads downwardly therefrom. This pipe may terminate with 35 an open end near the bottom of the drum, but preferably leads out through the end of the drum and is connected with an automatic discharge trap 13, see Fig. 1. The function 40 of the pipe will be explained hereafter in connection with the operation of the complete apparatus.

This present invention, which embraces 45 various like structures by which the defined purposes may be attained, comprehends the employment of tuyères, i. e. rotation inducing members, of differing constructions but all generally typified by the member 7 herein illustrated. Said member 7, as here 50 shown, is made up of a top ring 7^a, a plurality of angular or tangentially positioned tuyère blades 7^b and an imperforate bottom plate or disk 7^c. The inner edges of the blades substantially conform to or meet an 55 imaginary cylinder, indicated by the dotted circles 7^d of Figs. 4 and 5. This is true also of the inner periphery of the top ring 7^a, which also is substantially of a size with the 60 large opening 6^e in the bottom of the race member 6. Tuyère blades of either the over-

lapping arrangement of Fig. 4 or the nonlapping arrangement of Fig. 5 may be used. Being tangential to the aforesaid imaginary cylinder, both present tangential impact surfaces to the incoming fluid. The arrangement of Fig. 4 possesses the advantage of both forming and directing the entering streams upon the tangential impact surfaces. A common advantage flows from the fact that the blades form long and relatively thin slots or tuyère openings 7^x and hence, 70 collectively, subdivide the fluid into many thin streams that substantially parallel the axis of the tuyère ring. 75

The remaining feature, structurally considered, comprises an optional guard or hood which may or may not be used to prevent the dashing or splashing of slugs of fluid against the tuyère ring 7. This guard is shown in two forms. In Fig. 7 it appears 80 as an inverted pan 7^e; being either combined with or attached to the top ring 7^a, or the top casting. It serves to obviate the difficulties of side splashing and squirrel-caging 85 in the drum. The hood or guard of Fig. 7 90 comprises sides 7^f upstanding from the tuyère bottom 7^c, and is open at the top. Obviously the hoods surround and in large measure defend the open tuyères 7^x of the 95 tuyère ring. 95

Being of little altitude and being suspended from the top of the drum it is obvious that the bottom of this centrifugal fixture is well removed from the agitated surface of the liquid in the drum. The velocity of the emergence of the fluid at the nozzle varies with the difference of pressure within and without the drum. In practice these velocities are high. 100

In aggregate area the many tangential tuyères 7^x equal, or approximately equal, the area of the outlet opening in the top of the member 6. For some uses the aggregate area may be considerably less, whereas in other uses, where it is essentially desirable to avoid an arbitrary or artificial drop of pressure, the aggregate tuyère area may considerably exceed the area of the central outlet at the top of the fixture. 110

Approaching the fixture the vapor or other fluid impacts its surfaces. Finding exits between the tuyère blades and directed by the outer surfaces thereof the fluid is formed into the described relatively thin streams. These streams obviously enter the substantially cylindrical tuyère ring tangentially and encountering the annular arrangement of blades, combine to set up a very rapid whirling action within the tuyère ring and the top member of the fixture. On entering the tuyère openings the streams of fluid forthwith engage or impact the inner surfaces of the tuyère blades. Those surfaces being preferably tangential in position, conform to the nor- 120 125 130

mal angle of incidence of globules of liquid or particles carried by the streams of fluid. Due to this favorable position and relation the impact is non-disturbing in its effect upon the progress of such globules and particles and instead of being swept away they are virtually left or retained upon the inner surfaces of the tuyère blades. The accumulation of such impurities is proportionate to the quantity thereof present in the fluid passing through the fixture, and, as the deposit takes on the general whirling action of the body of fluid within the tuyère ring, that very whirling action insures the retention of the accumulated substances at the periphery of the whirling body, that is, on the inner periphery of the tuyère ring. As will be apparent, the general movement of the whirling body within the tuyère ring is axially toward the outlet 6^a, which affords a free passage for the purified fluid. The upward sweeping action results in lifting the deposit of impurities to the top of the tuyère ring and into the bottom opening of the race member 6. Arriving there, the deposit of impurities is immediately forced outwardly by the strong whirling action of the body of fluid within the fixture, that is, by centrifugal force. In this manner the heavier substances are positively and definitely removed from the main stream of fluid just prior to the escape of the fluid at the outlet. And obviously the heavier substances, whirling at relatively high velocity in the relatively remote race 6^a, are successfully retained in the race against possible removal by the outward sweep of the fluid. Indeed, the very effort of the fluid to escape longitudinally through the opening, irrespective of whirling action, tends to crowd the heavier substances into the remote parts of the immediately adjacent race.

Once arrived in the race the heavier substances whirling therein immediately encounter the substantially tangential peripheral discharge opening or nozzle 6^b and leave the fixture through that avenue.

Sufficient force is accumulated by the heavier substances to carry them well into the discharge pipe 12. This, added to the elevation of the fixture, admits of the return of the heavier substances to the under-surface portion of the fluid in the drum. Generally, however, it is preferred to get rid of the foreign substances by discharging them from the drum, as indicated in Fig. 1. The function of the trap 13 is to prevent the free escape of fluid from the drum and yet provide for the collection and intermittent discharge of the foreign substances.

Having thus described my invention, I claim as new and desire to secure by Letters Patent:—

1. The process of purifying fluids that consists in setting the fluid into motion toward

an outlet, causing and localizing the rapid rotation of the fluid adjacent said outlet and about the extended axis thereof, thereby separating the heavier substances centrifugally and withholding them from said axis, permitting a marked lateral expansion throughout the circumference of the whirling action immediately adjacent and in unobstructed centrifugal communication with said outlet and thereby laterally removing said substances from the fluid and from the margin of said outlet, and, completing the state of separation at a point immediately adjacent said outlet and so removed from the outlet, while permitting the purified fluid to depart through said outlet.

2. The process of purifying fluids that consists in causing and localizing the rapid rotation of a stream of fluid beneath an outlet prior to the exit of the fluid through said outlet while permitting the steady upward flow of the fluid, permitting a marked lateral unobstructed centrifugal expansion throughout the circumference of the whirling action immediately below said outlet and thereby laterally removing from the fluid the heavier substances, while permitting the purified fluid to rise through said outlet, and, discharging the heavier substances at a point directly beneath but laterally remote from said outlet.

3. A centrifugal fluid purifying device comprising, in combination, a hollow ring member and an internally smaller coaxial tuyère ring portion adapted to whirlingly direct the fluid into and through said member, said hollow member having a still smaller central outlet axially remote from said tuyère portion and also having a peripheral discharge nozzle.

4. A centrifugal fluid purifying device comprising, in combination, a hollow top member and an internally smaller coaxial tuyère ring portion beneath said member and adapted to whirlingly direct the fluid into and upwardly through said member, said hollow member having a still smaller central outlet in its top and also having a peripheral discharge nozzle.

5. A centrifugal fluid purifying device comprising, in combination, a hollow ring member and a smaller coaxial multiple tuyère member, closed at the end remote from said hollow member and adapted to whirlingly direct the fluid into and through said member, said hollow member having a still smaller central outlet axially remote from the tuyère member and also having a peripheral discharge nozzle.

6. A centrifugal fluid purifying device comprising a fixture casting containing a small and a large central opening and a larger intermediate race chamber, in combination with an annular multiple tangential tuyère member having a closed bottom

and attached to the bottom of said casting and opening directly into said race chamber, means fastening them together, and, a discharge nozzle leading from the 5 periphery of said race chamber.

7. In a device of the class described, an internal race member having a central outlet in its top and a peripheral discharge nozzle and also provided with an upright 10 collar for jointure with the wall of a container, in combination with means for clamping said member and collar endwise against said wall, and a multiple tangential tuyère member adapted to whirlingly 15 direct fluid into said race member and axially toward the outlet therein.

8. In a device of the class described a race member having a peripheral nozzle and a central discharge outlet opening in 20 combination with a multiply tuyère member adapted to whirlingly direct fluid into said race member and the plurality of bolt secured clips serving to fasten said members together.

25 9. A fluid container or drum having an outlet in its top in combination with a centrifugal fluid purifying device attached to

said top at said outlet opening and characterized by a collecting race immediately below said outlet, and a discharge pipe leading 30 from the periphery of said race.

10. In a device of the class described a top race member in combination with a bottom tuyère member, said race member having a central outlet and a peripheral discharge nozzle and a hood or guard partially enclosing said tuyère member. 35

11. The centrifugal fluid purifying device comprising a part containing a small and a large central opening and a larger 40 intermediate race chamber, the latter having a peripheral discharge nozzle, in combination with a multiple tangential tuyère ring, coaxial with said openings and having its end attached to the margin of the 45 large opening in said part, a bottom member closing the other end of said tuyère ring, and a fluid container enclosing said tuyère ring.

In testimony whereof, I have hereunto 50 set my hand this 24th day of November, A. D. 1924.

CHARLES GILBERT HAWLEY.
